UNITED STATES PATENT OFFICE.

HARRY BARTLEY REDFIELD, OF NEW YORK, N. Y.

TELEPHONE ATTACHMENT.

Application filed July 29, 1922. Serial No. 578,426.

The principal objects and advantages of my invention are the provision to a greater degree, in a telephone attachment, of:

1. Ample means for writing, and for referring to, such data as are usually desired, or either, while using the telephone;
2. Means which shall amply provide for writing and for referring to such data as are usually desired, or either, while using the telephone, and which is not in the way when the telephone or said means is not in use;
3. Means of each and all of the above mentioned characteristics which shall be simple to operate while using the telephone.

The first object is accomplished in part by having an element or elements of a telephone instrument or attachment which can be moved easily away from and back to its normal position. Such element or elements are also so designed that they can hold both writing and reference material or either. This principle is carried out in the illustration used, by a member designed to be pivoted so it can be swung from approximately a vertical position to approximately a horizontal position, and to be placed so as to be out of the way when not in use. Thus this principle provides greater available working surface in proportion to the space taken up when in its normal and operating position, and also makes it possible to place the attachment in a more appropriate place.

The second object is accomplished in part by the principle of designing the elements of a telephone attachment so that the principal dimensions or characteristic outline thereof are relatively similar to the dimensions or characteristic outline of some part of the telephone instrument and so that it can be so placed in relation to the part or parts of the telephone instrument that it takes up no space that is not allowed for in the usual handling of the telephone instrument itself, the same in this respect as though these means were integral with a telephone instrument of the usual design; and it also retains the other essential characteristics of a useful device of this class. This principle is fulfilled in the illustration selected by the designing of a complete attachment, in its normal position, of a length approximately the same as the standard of the telephone

instrument and of a width not great enough to interfere with the usual handling of the instrument, and adapted to be placed near the said standard.

The third result or object is carried out in part by the placing of the attachment designed upon the foregoing principles near the standard and by use of the pivoted element so that the movement of the hand or finger from the phone instrument will swing down the pivoted element, and this element will automatically return to its normal position and out of the way by a slight movement thereof. The tilting of the attachment at an angle against the standard of the telephone instrument at the top thereof, as shown, makes it possible to grasp the telephone instrument and the attachment together or to extend the fingers and thumb directly around the standard behind the attachment and move them with appreciably no greater effort or care than if there were no attachment on the telephone instrument.

The preferred example of these principles is shown in the drawings and are thus explained:

Figure I shows the attachment complete and fixed to a telephone instrument. Figure II shows one of the two principal members of the attachment which is numbered 1. Figure III shows the other principal member of the attachment which is numbered 7, and also the spring numbered 14 which actuates this member. Figure IV shows member numbered 15 and the manner of inserting the ends thereof into the holes in sides of member #7. Figure V shows the action of spring #14 when member #7 is pulled down. Figure VI shows means of fixing attachment to a telephone instrument.

The first member is numbered 1 and is composed of a flat piece of metal. Its sides #2 and #3 are bent at right angles to the main surface of the member. The lower end #4 of said member is grooved on the same side of the main surface of said member on which sides #2 and #3 are bent. This member is proportioned so that it can be placed against the standard of a telephone instrument and no part of it extend beyond the base of said instrument or take up more space than is generally allowed in handling

said instrument. In the lower portions of sides #2 and #3 are cut holes #5 and #6 placed so that rivets or other means of pivoting another member thereto may be placed 5 through them.

The member #7 is composed of a flat piece of metal. Its sides #8 and #9 are bent at right angles to the main surface of said member. The outside width of member #7 10 is slightly less than the inside width of member #1 so that member #7 will fit inside of the sides of member #1 throughout the length thereof. The lower end of said member is bent back against the main surface thereof in a curve between the two sides of #8 and #9, and is numbered 10.

In the lower portions of sides #8 and #9 are cut holes #11 and #12 in relative position to the two holes #5 and #6 in member 20 #1. Rivets are placed through the hole #5 in member #1 and hole #11 in member #7 and through hole #12 in member #7 and hole #6 in member #1, thus holding these two members in a pivoted position.

25 A piece of flat spring steel #14 is attached to both members #1 and #7. A piece of metal #15 is bent longitudinally so that its two edges lie against each other and the ends of said piece are bent to form round 30 longitudinal extensions at both ends which fit into small holes numbered 16 in the lower part of sides #8 and #9 of member #7 near the base thereof where said sides are bent in slightly. One edge of said spring is 35 inserted between the edges of said piece #15. The opposite edge of said spring is inserted into the grooved end #4 of member #1, thus closing the space between the ends of member #1 at #4 and of member #7 at 40 #10.

On member #1 is also cut two narrow fingers or rings #18 and #19 which are bent outwardly between the sides of said member and form an arc.

45 On member #1 in each side #2 and #3 thereof is cut a strip or finger #20 and #21 which is bent inwardly. These strips are cut away from the member for a short distance in from the sides so as to give it greater 50 spring qualities when certain metals are used.

In operation writing or reference material is fastened in member #7 under the end #10 thereof. Writing or reference material is placed also in member #1 by pulling 55 said member down an extra distance so that the ends of rings #18 and #19 will be a distance away from the bent lower end #10 of member #7 and inserting the circular fingers or rings #18 and #19 through holes 60 provided in such material. Where separate sheets of such material are used it is advisable that the outside sheet be relatively stiff to better resist wear at the edges by the strips #20 and #21.

65 Upon drawing member #7 up to approxi-

mately a horizontal position the spring #14 presses and twists outwardly and upwardly against the lower end of this member between the holes #16 and forces the other end of same upward and inward and close to 70 member #1. Both the pressure of spring in straightening itself and the more local pressure where piece #15 presses against a particular portion of the arc of the compressed spring when said piece #15 is held against 75 member #7 at #10 as is particularly shown in Figure V, is utilized. The sides #8 and #9 thereof being pivoted on inside of sides #2 and #3 will completely close against the material inserted in the attachment. 80

Thus the two members will be automatically closed against one another and remain so until member #7 is again drawn down close to the table on which the instrument rests, when the index sheets or other material in member #1 will remain up by reason of the strips or fingers #20 and #21 in each side of said member pressing against the sides of the sheets therein or any part of same which is not purposely pulled down. 90 The memoranda pad or other material in member #7 will also be revealed in an approximately horizontal position at the same time. When member #7 approaches close to the table the action of the spring 95 reverses and moves said member down to the limit of its movement, by reason of the pressure of said spring in straightening itself passing the line of the pivoted center sufficient to overcome the pressure of piece 100 #15 against the arc of the compressed spring. When member #7 is pulled above this point said member will again continue to move up and against member #1 and will also return thereto any material placed in 105 member #1 which may have been pulled down from it.

In member #1 are cut two vertical or longitudinal flanges #22 and #23 which are bent back and in opposite direction from 110 sides #2 and #3. The edges of these flanges are bent at approximately 30 degrees. A collar #24, proportioned to extend nearly around the standard of the telephone instrument has its longitudinal edges bent at an 115 angle appropriate to receive the edges of flanges #22 and #23. A screw passes through each flange and with a nut thereon tightens the said flanges and collar around and against the standard. The lower part of the flanges #22 and #23 is wider than the upper part which causes the attachment 120 to tilt away from the standard at the bottom sufficient for the fingers to be inserted between member #1 and the standard of the telephone instrument, and also to cause the movable paper inserted in member #1 to rest back against said member #1. 125

It is contemplated to apply these principles or a part of same to provide an attach- 130

ment solely for writing purposes or solely for reference purposes, as well as for the combination of both.

Where the word "attachment" is used, particularly in the claims, it is used as meaning any part of a telephone system; and contemplates forming an integral part of a telephone receiving and sending instrument, or a separate unit applied thereto such as on a desk instrument or on a switchboard,— except where specifically limited to one of the above purposes.

I claim:—

1. The combination, in a telephone attachment, of a member the side edges or portions of which are at approximately right angles to the main surface thereof and adapted to hold the bottom portions of cards between said sides so that same may be swung outwardly from the top thereof, and a second member, adapted to hold paper, attached movably to said first member and lying normally adjacent to the edges of the sides of the first member.

2. The combination, in a telephone attachment, of a member the side edges or portions of which are at approximately right angles to the main surface thereof and adapted to hold the bottom portions of cards between said sides so that same may be swung outwardly from the top thereof, and attached vertically to the upright member of a telephone instrument, and a second member, adapted to hold paper, attached movably to said first member, and means to automatically move the second member through a desired portion or portions of its prescribed movement.

3. The combination, in a telephone attachment, of a member with flat sides at approximately right angles to the main surface thereof and rings on the lower portion of said member so paper attached to said rings may be moved in an arc away from said member at the top thereof, and a second member, adapted to hold paper, attached movably to said first member at the flat sides thereof.

4. The combination, in a telephone attachment, of a member with flat sides at approximately right angles to the main surface thereof and adapted to hold paper, and a second member with flat sides at right angles to the main surface thereof adapted

to hold paper and attached movably to said first member at the flat sides of each member.

5. The combination, in a telephone attachment, of a member with flat sides and adapted to hold the lower edges of cards on the lower portion of said member so the top of said cards can be swung outwardly, and adapted to be attached vertically to the principal upright member of a telephone instrument, and a second member with flat sides and adapted to hold paper, and attached movably to said first member at the flat sides of each member, and means to automatically move said second member through a desired portion or portions of its prescribed movement.

6. The combination, in a telephone attachment, of a movable member and a spring adapted to actuate said member by the pressure caused by the ends of the compressed spring in straightening itself and also by the lateral pressure of the bending portion of said compressed spring as said bending portion presses against the edge of said movable member.

7. The combination, in a telephone attachment, of a movable member and a spring adapted to move said member in one direction by the pressure of the ends of said spring in straightening itself and by the lateral pressure of the arc of the compressed spring as said arc is forced against the edge of said movable member, and in another direction by the pressure of the end of said spring as it moves past the line between the center of the pivot of said movable member and the stationary end of said spring, thus overcoming the pressure of the arc of the compressed spring.

8. The combination, in a telephone attachment, of a member bent longitudinally so that its opposite longitudinal edges approximately meet and round projections at each end thereof adapted to fit eccentrically and semi-rotatably into a movable member, and a flat spring one end of which is adapted to be held in said semi-rotatable member and the opposite end of said spring adapted to be held in a stationary member to which the movable member is connected so that said spring will be bent so as to counteract the movement of said movable member.

HARRY BARTLEY REDFIELD.
